(57) **CLAIM**

The ornamental design for an absorbent article substrate with a pattern, as shown and described.

DESCRIPTION

FIG. 1 is a front view of an absorbent article substrate with a pattern;

FIG. 2 is a another front view of an absorbent article substrate with a pattern;

FIG. 3 is a rear view of the absorbent article substrate with a pattern shown in each of FIGS. 1 and 2;

FIG. 4 is a top end view of the absorbent article substrate with a pattern shown in each of FIGS. 1 and 2;

FIG. 5 is a left side view of the absorbent article substrate with a pattern shown in each of FIGS. 1 and 2;

FIG. 6 is a right side view of the absorbent article substrate with a pattern shown in each of FIGS. 1 and 2; and,

FIG. 7 is a bottom end view of the absorbent article substrate with a pattern shown in each of FIGS. 1 and 2.

The broken lines, including those showing the diaper tabs and ears, are included for the purpose of illustrating environment and form no part of the claimed design.

1 Claim, 4 Drawing Sheets
